2 Claims. (Cl. 260—239.9)

The present invention relates to the provision of a new sulfonamide derivative, and to a process for producing the same.

5-sulfanilamido isoxazoles and methods for producing such compounds have been described in U.S. Patent No. 2,430,094. The synthesis of 3-sulfanilamido isoxazoles, however, in which the sulfanilamido group is bonded to the third position of the isoxazole nucleus has not been reported heretofore in the literature. The principal object of the present invention is to provide such a compound possessing chemotherapeutic utility equivalent to that normally possessed by known sulfa derivatives of the general class described. In particular, the invention contemplates the provision of the compound 3-sulfanilamido-5-methylisoxazole.

During the course of a systematic search for new

2

In contrast to the foregoing results, the in vivo testing of the same compounds demonstrated a clear superiority for the unique compound of the invention. That is to say, by administering our sulfonamide derivative to groups consisting of ten mice each weighing 17-18 grams, via the oral route at 2, 24, 48, 72 and 96 hours, respectively, following intraperitoneal injection of 100MLD of the microorganism *Diplococcus pneumoniae* (type 1), 80 and 10 survival percentages at the dosage level of 1 and 0.5 milligram per gram of body weight were observed, whereas sulfisoxazole gave 50 and 0 percent at the dosage level of 2 and 1 milligrams in analogous experiments. The infections were fatal to all untreated animals; the ST-100 being two days. As a result of these experiments, it was shown that the sulfonamide of the invention is more than two times more effective than sulfisoxazole when administered via the oral route. 3-sulfanilamido-5-methylisoxazole may be represented by the following structural formula:

20 The novel compound of the invention may be produced by condensing 3-amino-5-methylisoxazole with a compound carrying a p-amino- or a p-substituted benzene sulfonyl group, and thereafter changing the N⁴-substituent into a N⁴-amino group in the latter condensation. 25 30 This reaction may be illustrated by the following structural equations:

wherein R is the residue of an easily reactive p-substituted benzene sulfonic acid derivative; and R' represents a group which is convertible to an amino group.

45 In the foregoing reaction, the condensation steps A and A' may be effected without the use of a solvent, but an inert solvent medium generally insures the promotion of uniform reactions. In general, the type of solvent employed is determined by its non-reactivity, but if sulfonyl halides are used as the easily reactive derivatives of benzene sulfonic acid, basic or basified solvents such as pyridine, picoline or acetone with sodium bicarbonate are preferably employed. We prefer to 50 employ benzene sulfonyl halides, and particularly the chloride, as the easily reactive derivative of benzene sulfonic acid, but other functional derivatives of benzene sulfonic acid, for example, the acid ester, may also be employed.

55 60 Step B in the foregoing synthesis is effected subsequent to the step A', in which 5-methyl-3-benzene sulfonamido isoxazole, bearing a substituent convertible to an amino group at the fourth position of the benzene nucleus, is produced. The aforementioned substituent at the 4-position of the reactive benzene sulfonic acid derivatives

65 may include any of the nitro-acylamino or carbalkoxy-amino groups. The type of reaction employed in step B is determined largely by the nature of substituent R'. That is to say, when R' is an acylamino radical such as the acetamino group or a carbalkoxyamino radical such as the carbethoxy amino group, the intermediate should be saponified, whereas when R' is a nitro group, the inter-

sulfonamide compounds structurally related to sulfisoxazole, and evaluation of the antibacterial activity of such compounds, we have succeeded in synthesizing 3-sulfanilamido-5-methylisoxazole, and have found that this compound exhibits a high degree of antibacterial activity in both in vitro and in vivo tests. That is to say, the antibacterial activity of the unique compound of the invention in vitro is similar to that of sulfisoxazole, whereas the antitubercular activity in vitro of said compound is found to be superior to that of sulfisoxazole. The in vitro data for the novel compound of the invention as compared with sulfisoxazole are as follows:

Test organisms	3-Sulfanilamido-5-methylisoxazole (mol)	Sulfisoxazole (mol)
<i>Shigella dysenteriae</i> (Shiga)	1:500,000	1:500,000

3
mediate should be reduced. These reactions may be effected in accordance with standard techniques, for example, by heating with aqueous sodium hydroxide solution for the hydrolysis reaction, or by treating with zinc dust and hydrochloric acid for the reduction reaction.

It should be noted that the starting material 3-amino-5-methylisoxazole utilized in the foregoing reaction is also a new compound. It may be obtained by hydrolysis of ethyl 5-methylisoxazole-3-carbamate succeeding to the Curtius' degradation of 5-methylisoxazole-3-carboxylic acid according to Freiri's method (cf. CA-26, 5953, 1932). The compound is prismatic and melts at 61-62° C.

It is believed that our invention may be best understood by reference to the following specific examples showing the application of the foregoing techniques to the production of the unique sulfonamide of the invention:

Example

(a) *Preparation of 3-amino-5-methylisoxazole.*—1.7 g. of ethyl 5-methylisoxazole-3-carbamate was heated on a boiling water-bath with 5 cc. of a 10% aqueous sodium hydroxide solution for 8 hours, then the reaction mixture was extracted several times with ether or benzene and the extract was cooled succeeding to the removal of the solvent and drying. The residue was solidified after a while and gave prismatic crystals, melting point 61-62° C., of 3-amino-5-methylisoxazole by recrystallization from benzene.

Elemental analysis for empirical formula $C_4H_6ON_2$: Calculated—C, 48.97; H, 6.16; N, 28.57. Found—C, 49.42; H, 6.50; N, 28.28.

This substance is a new compound and is also obtained by a similar hydrolysis of benzyl 5-methylisoxazole-3-carbamate, melting point 80-81° C.

(b) *Preparation of 3-acetylsulfanilamido-5-methylisoxazole.*—0.9 g. of 3-amino-5-methylisoxazole in 5 cc. of pyridine was allowed to react with 2.0 g. of acetyl-sulfanil chloride accompanied with the generation of heat. After about one hour, water was added to the reaction mixture and the crystal precipitated out was recrystallized from alcohol to give 2.5 g. of 3-acetylsulfanilamido-5-methylisoxazole, melting point (decomposition) 220-221° C.

Elemental analysis for empirical formula $C_{12}H_{13}O_4N_3S$: Calculated—C, 48.81; H, 4.40; N, 14.33. Found—C, 49.08; H, 4.63; N, 14.05.

A similar result was obtained by the condensation in a sodium bicarbonate-acetone medium.

(c) *Preparation of 3-sulfanilamido-5-methylisoxazole.*—2 g. of 3-acetylsulfanilamido-5-methylisoxazole was heated with 10 cc. of an aqueous sodium hydroxide

5
solution on a water-bath for one hour and after cooling the reactant was acidified by addition of acetic acid. The precipitate thus formed was recrystallized from dilute alcohol to give 15 g. of colorless prisms of 3-sulfanilamido-5-methylisoxazole, melting point 167° C.

Elemental analysis for empirical formula $C_{10}H_{11}O_3N_3S$: Calculated—C, 47.43; H, 4.35; N, 16.60. Found—C, 47.96; H, 4.49; N, 16.52.

10 This compound is bitterish and by acetylation in pyridine base gave the corresponding N^1,N^4 -diacetyl compound, melting point 209-210° C.

Having thus described the subject matter of our invention, what it is desired to secure by Letters Patent is:

15 1. The chemical compound 3-sulfanilamido-5-methyl-

isoxazole, as represented by the formula:

20 2. Process for the production of 3-sulfanilamido-5-methylisoxazole that comprises, reacting 3-amino-5-methylisoxazole by condensing the same within an inert solvent medium with a benzene sulfonic acid derivative selected from the group consisting of esters and halides of p-aminobenzenesulfonic acid, p-acylaminobenzenesulfonic acid, p-nitrobenzenesulfonic acid, and p-carboalkoxyaminobenzenesulfonic acid to produce a reaction product consisting of the corresponding p-substituted benzene sulfonyl derivative represented by the formula:

30 35 wherein R represents a substituent member selected from the group consisting of amino, acylamino, nitro and carboalkoxyamino radicals, and treating said reaction product for the separation and recovery of the desired 3-sulfanilamido-5-methylisoxazole.
